(57) **CLAIM**

The ornamental design for an ice box with bullet-shaped reusable ice cubes, as shown and described.

DESCRIPTION

FIG. 1 is a front view of the ice box with bullet-shaped reusable ice cubes showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof, wherein the lid of the ice box with bullet-shaped reusable ice cubes is open; and,

FIG. 9 is another perspective view thereof, showing its bullet-shaped reusable ice cubes.

1 Claim, 9 Drawing Sheets

FIG. 1

FIG. 2

FIG. 3

FIG. 4

FIG. 5

FIG. 6

FIG. 7

FIG. 8

FIG. 9
